ROPE DISPENSER

Filed May 10. 1929

INVENTOR.
Fred Brinner

W. J. Beck
Att'y.

UNITED STATES PATENT OFFICE

FRED BRINNER, OF MASON CITY, ILLINOIS

ROPE DISPENSER

Application filed May 10, 1929. Serial No. 362,015.

My invention relates more particularly to devices for use in stores and other places where various sizes or grades of rope are sold or from which the rope is distributed and wherein it is desirable to permit a ready inspection of the various sizes or grades, and in which it is also desirable to provide means for measuring the quantity of rope dispensed, and for cutting the rope at the proper point.

One object of my invention is the provision of a stand having a head portion provided with means for holding the ropes against back running, the stand being so arranged that between the head portion and the support, a considerable length of rope is exposed so that it may be inspected to permit ready selection.

Another object of my invention is the provision of a simple and efficient measuring rod or device which may be adjusted to any convenient position around the head portion and by means of which the rope may be measured after it is drawn through the head portion.

Another object of my invention is the provision of a simple and efficient cutting member or knife which is mounted in such a manner that when not in use its cutting edge lies within the head portion and is protected thereby to prevent accidental injury to any person adjacent the machine.

Other objects of my invention will appear and be described in the specification.

The novelty of my invention will be hereinafter more fully set forth and specifically pointed out in the claims.

In the accompanying drawings:

Fig. 1 is a central sectional side elevation of a device embodying my invention.

Fig. 2 is a plan view or a part of the head portion, partly broken away to show the mounting for the cutting knife.

Fig. 3 is a plan view of the head portion of the device with the outer shell removed.

Fig. 4 is a sectional detail showing the cutting knife elevated to cutting position.

The same numerals of reference are used to indicate identical parts in all the figures.

As showing one form of construction em-

bodying my invention though without limiting myself to the precise detail of construction or arrangement of parts shown or to be herein described but availing myself of all changes and modifications that may be made within the terms of the appended claims, I have shown a device consisting of three main portions, namely the head portion, the column, and the base.

My present device has been planned so that it is well adapted to be made from pressed steel parts of simple construction and arrangement which are easily assembled, though it is obvious that other processes of production may be used in making the device.

Because of their simplicity I will describe the column and base first.

The column consists of a tubular portion 5 pressed or otherwise suitably secured in the upstanding flange of the base 6, and carrying upon its upper end the inner member 7 of the head portion, this latter being pressed or otherwise suitably secured upon the upper end of the column 5.

The base section is somewhat like an inverted saucer and carries the centrally arranged upstanding flange in which the column 5 is mounted, the base being perforated as at 8 to permit the passage of ropes so through it to the head portion. The base is suitably secured to the floor as by screws passing through perforations 9 conveniently arranged around the edge of the base.

The head portion comprises the inner member 7 which is formed with a central sleeve-like portion to engage the upper end of the column 5, a conical portion 10 extending downwardly and outwardly therefrom and terminating in a cylindrical portion 11, over which the outer member or shell 12 engages, and to which it is secured as by screws or bolts 13.

This outer shell passes upward from the cylindrical portion 11 and has a flat top 14 which is provided with a series of perforations 15, of various sizes to permit the passage of the various ropes, these perforations 15 being arranged around the edge of the flat top 14 as better shown in Fig. 2, 100

the flat top 14 being also centrally perforated to permit the passage therethrough and movement therein of the measuring rod 16.

This measuring rod 16 is preferably formed at its lower end as shown at 17 where it is bent at a right angle and provided with a collar, its upper end carrying a ball or handle 18, the rod being provided with graduations 19 suitably arranged to permit 10 the measurement of rope in any desired units.

The wall of the outer member 12 is provided with a pair of vertical slots 20, preferably arranged on opposite sides, and a cutting off knife 21 passes through each of these slots 20, the upper end of each knife being pivotally mounted between a pair of lugs 22, welded or otherwise suitably secured on the inside of the upper portion of 20 the outer member 12, the lower end of the knife 21 carrying a hemisphere 23 on each side the latter serving as a guard for the lower end of the knife and also as a means for the ready movement of the knife either 25 by the rope or by hand.

The knife 21 is preferably serrated on its cutting edge as shown at 24 Figs. 1 and 4, somewhat after the design and arrangement of a serrated bread knife.

80 Referring now more particularly to Figs. 1 and 3, it will be noted that the conical portion 10 of the inner member 7 is provided with perforations 25, aligned with the perforations 15 in the top 14 and with the 35 perforations 8 in the base 6 so that the ropes may pass through the device, and this conical portion 10 is also provided with a row of slots 26, each of which receives the reduced end of a dog 27.

40 The dogs 27 are preferably shaped as shown in Fig. 3, are serrated at their outer ends, and beveled at their upper edges to form a series of rope engaging teeth or points and the slots 26 are made sufficiently 45 large to permit the outer ends of the dogs 27 to have sufficient movement to release or grip the rope, the dogs falling by gravity into contact to grip it and prevent a downward movement through the head portion.

50 If it should be desired to move any rope downward, the reduced inner end of its dog may be operated by reaching under and into the cone 10, to raise the dog out of engagement with the rope and permit it to be 55 moved downwardly.

The operation of the device is as follows, assuming that the device is properly set up and secured to a floor which is perforated to permit the ropes to pass through it, the ropes 60 being stored in quantity in the basement or other space below the floor and the end of each rope passed up through the device and projecting through the top a short distance. After the desired size or quality of rope has 65 been selected, the operator grasps the knob

on the upper end of the measuring rod 16, raises this rod and turns it to bring the collar on the bent end 17 against the underside of the top 14 whereupon the rod rests upon the top in a horizontal position, adjacent the rope to be handled. The operator next pulls out as much rope as is desired, measuring it as it is pulled out and upon pulling the desired quantity, passes the rope under the nearer of the two cutting knives and by an upward and outward movement of the rope against the knife, severs the rope and then replaces the measuring rod by raising it up to a vertical position and then lowering it into the column. Upon severance 70 of the rope the end next the device is simply released and is at once caught by its dog and held against running back, though the rope is always free to be pulled out as upon upward movement its dog raises and slides 75 along the rope ready to engage it upon a downward movement.

It is to be noted that the form and arrangement of the device lends itself readily to production from sheet metal, and further 80 that there are no operating parts within the machine which are complicated either in their construction, arrangement, or mounting.

Having thus fully described my invention, 85 I claim:

1. In a rope dispenser the combination of a base, a column secured thereto, a head portion carried by the upper portion of the column and provided with a plurality of 100 rope passages therethrough, and rope gripping means adjacent each rope passage.

2. In a rope dispenser the combination of a base provided with a plurality of rope passages, a column carried thereby, a head portion carried by the column and provided with a plurality of rope passages aligned with the passages of the base whereby when a rope is in a passage a portion of its length will be exposed, rope gripping means adjacent each passage, and rope cutting means carried by the head portion.

3. In a rope dispenser the combination of a base, a column carried thereby, an inner head member carried by the column, an outer head member associated therewith and provided with rope passages therethrough, and rope gripping means within the space between the inner and outer head members.

4. In a rope dispenser the combination of an inner head portion, an outer head portion, there being rope passages in the outer head portion, rope gripping means adjacent said passages, a knife mounting comprising in part a slot in the outer head portion, a knife mounted for movement into and out of said slot, one end of said slot forming a movement limit for the knife when in cutting position.

5. In a rope dispenser the combination of,

an inner conical shaped head member, an outer cup shaped head member, means for securing the outer head member to the inner head member, their being aligned rope passages formed through both members and a 5 rope gripping dog carried by the conical portion of the inner head member and adjacent each rope passage.

6. In a rope dispenser the combination of a column, a head portion surrounding the 10 upper end of the column and having rope passages therethrough spaced around the column, rope gripping means associated with each passage, a rope measuring device mounted adjacent the upper end of the 15 column and normally occupying a position within the column but movable to extended position and to any point around the head portion and provided with graduations for 20 measuring in pre-determined units.
